Alexander Bonnell Tappen Inventor
By his Attorney
Andrew J. Nease

UNITED STATES PATENT OFFICE.

ALEXANDER BONNELL TAPPEN, OF BRIARCLIFF MANOR, NEW YORK.

METAL GRATING.

Application filed July 13, 1921. Serial No. 484,365.

To all whom it may concern:

Be it known that I, ALEXANDER BONNELL TAPPEN, a citizen of the United States, residing at Briarcliff Manor, in the county of Westchester and State of New York, have invented certain new and useful Improvements in Metal Gratings, of which the following is a specification.

My invention relates to improvements in grating for sidewalks, covers and the like, and the object of my invention is to provide a simple, convenient and efficient grating for the purpose of ventilation and the like. I accomplish this object by the device illustrated in the accompanying drawing in which

Figure 1 is a perspective view of the device;

Figure 2 is a cross section on the line 2—2 of Figure 1, and

Figure 3 is a cross section of a modification of the device whereby several sections may be joined together.

Similar characters of reference refer to similar parts throughout the several views.

My improved grating is preferably stamped from a sheet of steel, iron or other metal. The two marginal edges 1 and 2 of the blank are bent downward at right angles to the intermediate central section 3 and a plurality of counterpart lateral leaves 4 are formed by cutting spaced rectangular sections on three sides and bending down the cut out sections thus formed, at right angles to the body of the blank. I thus provide a series of lateral spaced bars 6 extending from side to side of the grating section and which will serve to strengthen and stiffen the intermediate bars 6 between the slots 5.

I prefer to provide narrow uncut strips 7 and 8 respectively intermediate the slots 5 and the downwardly bent marginal edges 1

and 2. The marginal edge 2' of the bent-over edge section 2 may be bent inward for the purpose of strengthening and stiffening the device, if desired.

I find it desirable in some cases to join together in group formation a plurality of the grating sections and this may be accomplished by the optional form of the device illustrated in Figure 3 in which a marginal edge section 7 of the bent-over flange 8 is bent outward and upward forming a channel 9 in which the flange 10 of adjoining section may be seated whereby a plurality of the grating sections may be joined together.

Having thus described my invention what I claim is:

1. A grating section having its marginal sides bent downward, spaced lateral bars extending from side to side and provided with integral rectangular strengthening leaves formed by bending down adjacent cut out sections and having a marginal side bent to form a channel.

2. In a grating section the combination of two marginal downwardly bent edge sections, a plurality of rectangular lateral sections cut out on three sides and bent downwardly forming spaced lateral bars with integral strengthening leaves depending therefrom and uncut sections intermediate the ends of the slots and the downwardly bent edges of the grating section.

In testimony whereof, I have signed my name to this specification in the presence of two subscribing witnesses, this 6 day of July 1921.

ALEXANDER BONNELL TAPPEN.

Witnesses:

C. STEUART ASHLEY,
DANIEL J. DOWLING.
